STEPHEN T. SMITH, OF STAMFORD, CONNECTICUT, ASSIGNEE TO UNDERWOOD TYPE-WRITER COMPANY, OF NEW YORK, N. Y., A CORPORATION OF DELAWARE.

TYPE-WRITING MACHINE.

1,169,295.

Specification of Letters Patent. Patented Jan. 25, 1916.

Application filed November 16, 1912. Serial No. 731,871.

To all whom it may concern:

Be it known that I, STEPHEN T. SMITH, a citizen of the United States, residing in Stamford, in the county of Fairfield and 5 State of Connecticut, have invented certain new and useful Improvements in Type-Writing Machines, of which the following is a specification.

My invention relates to page-end indicating devices, and has for one of its objects to provide means by which the operator may see at a glance how near the end of the work sheet has approached to the printing point.

Another feature is to so construct the device that it may be attached to the typewriter as a unit, without requiring a change in the construction of the usual machine.

The indicator may comprise a pointer 20 rotatable over a dial which may be formed on a cover plate of the platen frame. The pointer may be fixed to a shaft journaled in said plate, to which shaft is also secured a crown gear connected through an idler gear 25 to a pinion on the platen shaft, the pointer thereby being rotated over the dial as the platen is rotated. A second pointer which may be loosely mounted on the shaft carrying the first pointer, is adjustable to any 30 position over the dial and may be yieldingly held in adjusted position by depressions or notches in the dial, which notches may also form the scale markings on the dial. The adjustable pointer is set at an angle to the 35 pointer driven by the platen, corresponding to the length of the work-sheet, so that the distance between the two pointers at any time during the writing of a work-sheet indicates the nearness of the writing line to 40 the end of the work-sheet, the pointers being brought together when the platen has been rotated to bring the last line to be written on the work-sheet to the printing line on the platen.

In the accompanying drawings, Figure 1 shows my invention attached to an Underwood typewriter carriage. Fig. 2 is an end elevation view showing how the pointer is driven by the platen axle. Fig. 3 is a top 50 plan view of the device. Fig. 4 is a front sectional elevation view of the same. Fig. 5 is a detail view showing the depressions on the dial for holding a pointer in adjusted position.

The usual platen 1, fixed upon an axle 2

journaled in the ends 3, 4 of the carriage 5, may be rotated by a line space lever 6, which operates a pawl 7 to drive a ratchet wheel 8, also fast on the said axle 2.

The work sheet 9 is held to the platen by feed rolls 10. The feed rolls are somewhat below the writing line 11, and as the operator cannot see if the sheet is still held by the rolls, it often happens that the paper is inadvertently fed beyond the rolls. To prevent this, and to provide for a bottom margin of any predetermined width, I have arranged an indicating device by which the operator may accurately tell the space remaining at the bottom of the work sheet, 70 which device is constructed as follows: A pinion 12 on the platen axle 2 is geared through an intermediate gear 13 to a crown gear 14 fast on a shaft 15, to which is also fixed a pointer 16 arranged over a 75 dial 17 having markings or graduations 17^a which correspond with the line space movements of the platen. When the platen is rotated, the motion is transmitted through the train of gears 12, 13, 14 to the pointer 80 16 which indicates the extent of travel of the platen 1. If, for example, a work sheet is used upon which eighty lines can be written, the pointer 16 starting from the zero mark will have moved to the eightieth 85 graduation when the last line space of the sheet is reached. By resetting the pointer to zero when a subsequent sheet is inserted, the operator will know that the last line is being written on the new sheet when the 90 pointer again reaches "80" on the scale.

In order that the operator may more easily perceive the point at which he must stop writing, an auxiliary pointer 18 is placed over the dial. This pointer 18 is 95 loosely mounted for rotation relatively to the shaft 15, and is preferably made of spring metal, so that the point 19 may spring into the depressions formed by the scale markings 17^a to prevent accidental displacement. To facilitate positioning, the pointer 18, the upper part of its hub 20 is formed into a knurled finger-piece 21. To permit handling the device as a unit, to be quickly attached or detached, the dial 17 is 100 formed as part of the right end carriage cover plate 22, upon which the pointers 16, 18 and the gears 13, 14 are also mounted, and the entire device held to the carriage by means of the screws 23.

Variations may be resorted to within the scope of the invention, and portions of the improvements may be used without others.

Having thus described my invention, I claim.

1. In an indicating mechanism for type-writing machines, in combination with a rotary platen, a dial graduated to accord with line spaces on the platen, a pointer adapted to move over said dial, gearing on the shaft of said platen adapted to cause movement of said pointer in time with line-spacing movement of the platen, a second pointer, adjustable about the dial, into positions to indicate limit of permissible movement of the first pointer over the dial and means whereby said second pointer is held fixed but yielding in said positions. 65
2. In an indicating mechanism for type-writing machines, in combination with a rotary platen, a dial graduated to accord with line spaces of the platen, a pointer adapted to be moved over said dial, gearing on the shaft of said platen adapted to cause movement of said pointer in time with line-spacing movement of the platen, and a second pointer yieldingly adjustable over the dial into fixed but yielding positions, and means on said dial coöperating with said second pointer in maintaining its fixed but yielding position. 70
3. In an indicating mechanism for type-writing machines, the combination of a dial plate having a series of notches or depressions, a pointer adjustable over the dial plate and yieldingly held by said depressions in adjusted position, and a second pointer geared with the platen axle to travel over said dial plate. 75
4. In an indicating mechanism for type-writing machines, the combination of a dial plate provided with an annular series of notches, a shaft journaled in said plate, gearing connecting said shaft with the platen shaft, a pointer fixed to said shaft to rotate over the plate, and a second pointer loosely mounted on said shaft to yieldingly engage said notches to thereby hold it in any position of adjustment. 80
5. In combination with a platen, a page-end indicating device comprising a dial, a pointer geared to the platen shaft to move over the dial as the platen is rotated, to progressively denote the number of lines written, and an auxiliary pointer capable of being set at different positions over said dial and held in set position by means of its point entering a depression of the dial, to indicate the full number of lines to be written, and the completion thereof. 85

6. The combination with a platen and a platen frame, of a page-end indicating device comprising a plate on said frame having a dial formed thereon, a pointer adapted to travel over said dial, and a driving connection between the platen and the pointer, said pointer and driving connection being supported in operative relation by said plate, means on said plate whereby the plate may be connected to a platen frame. 90

7. A page-end indicating device composed of two units in order to be more readily applicable to a typewriter platen frame having a revoluble platen, one of said units comprising a pointer, driving means whereby said pointer may be operatively connected with the platen, to move therewith, a second pointer to coöperate with said first-named pointer, and a plate forming a mount for said driving means and pointers, and the second unit comprising a pinion to be secured to the platen axle. 95

8. The combination with a platen, of a page-end indicating device comprising a dial, a pointer geared to the platen whereby it is made to travel over said dial with the rotation of said platen, to progressively denote the number of lines written, a pointer set frictionally in a fixed position over said dial to continually indicate the full number of lines to be written, a plate for carrying said dial, pointers and gearing, and means for attaching said plate to the frame of a platen. 100

9. The combination with a typewriter carriage having a platen, of a plate, a page-end indicating device comprising a dial formed on said plate, an adjustable indicator therefor, a pointer traveling over the dial toward said indicator, and driving means between the platen and pointer, whereby said pointer is operated by the rotation of said platen, said plate forming a cover and support for the said driving means. 105

10. The combination with a typewriter carriage having a platen, of a page-end indicating device constructed to be easily attachable to the platen and comprising a plate carrying a dial, a pointer, driving means connecting the platen with the pointer, whereby said pointer is operated by the rotation of the platen, and a second pointer capable of being set frictionally in a fixed position by hand to continually indicate the full number of lines to be written. 110
